UNITED STATES PATENT OFFICE.

SILVESTER NUNN, OF PORTLAND, OREGON.

ELECTRIC-WIRE INSULATOR.

1,146,201.

Specification of Letters Patent. Patented July 13, 1915.

Application filed April 12, 1912. Serial No. 690,297.

To all whom it may concern:

Be it known that I, SILVESTER NUNN, a citizen of the United States, residing at Portland, in the county of Multnomah and State of Oregon, have invented a new and useful Electric-Wire Insulator, of which the following is a specification.

My invention relates to insulators for telegraph, telephone and other electric line wires, and has for its object to provide an insulator, which is simple in construction, cheap to manufacture and highly efficient in use, and which will permit slack to be taken up from fully a mile of line in one operation.

Other objects and advantages of my invention will appear in the course of the following description.

In the accompanying drawings:—Figure 1 is an elevation of my improved insulator. Fig. 2 is a vertical sectional view of the same. Fig. 3 is a top plan view of the insulator with the cap removed.

Referring to the drawing, which illustrates the preferred form of my invention, 5 designates the body of the insulator, which is cylindrical in its general outline. Its external shape does not differ radically from the ordinary insulators. The body is provided with an upwardly extending centrally disposed socket or recess 6, which extends inwardly from the lower end or bottom and has its upper part tapered and screw threaded for the reception of the usual supporting pin. The lower part of the recess is unthreaded and slightly enlarged in diameter 35 to form a hood 7. As illustrated the lower edge of the hood is oppositely beveled from the inner and outer sides so as to meet at a circular intermediate edge 8, which constitutes a water drip for the insulator.

The body 5 is gradually tapered or inclined inwardly from its lower end to a point just above its center where it is abruptly curved outwardly and around to 45 form a projecting circumferential rib 9, and is then curved around inwardly to form an adjoining groove 9^a. From the upper edge of the groove, the side of the body is extended up straight and then cut inwardly to 50 form a beveled edge 10.

Centrally of the top of the body 5 is an integral vertical projection 11 which is formed by reducing the diameter of the body, thereby leaving a flat shoulder 12 at 55 the base of the projection. The projection is provided with a diametrically disposed ver-

tical slot, 13, which extends entirely through the projection and down into and diametrically through the upper part of the body 5, forming horizontally disposed laterally extending branches. The bottom of the slot is concaved or curved in cross section, and is straight along its bottom except at the outer ends of the said branches, where that portion of the slot which extends through the top of the body is outwardly beveled or flared to form lips 14. The vertical slot and the branches thereof form a wire receiving passage extending through the insulator.

The projection 11 is exteriorly screw threaded, and adapted to be screwed on said projection is a cylindrical cap or top 15 provided with a rounded outer face. The cap 15 is hollowed out to form a centrally disposed circular recess 16, which is screw threaded in its side walls and of such a depth, that when the cap is screwed down into place, the lower end of the cap will rest upon the shoulder 12 of the body 5, whereby the sides of the cap will close and cover that part of the slot 13 which extends through the projection 11.

The bottom of the cap is of a diameter corresponding to that of the top of the body, and the cap at its lower outer edge is oppositely beveled, as at 17, with respect to the bevel 10 at the top of the body. Also the bevel 17 at the lower edge of the cap corresponds in size with the beveled or flared terminals or lips 14 of the branches of the vertical slot 13, and beveled portions of the screw cap will always lie above the beveled terminals 14 of the branches of the slot 13. This construction will enable an insulated wire or an uninsulated wire to be drawn through the passage way of the insulator and pulled from above or below the passage without injuring the wire.

My insulator, which can be made of molded glass, glazed porcelain or other suitable material, constitutes an improvement over similar devices in that lengths of line wire supported and passing through a number of insulators, can be freely moved horizontally from one point to take up slack in the wire, without touching the insulators, for with my insulator the wire has a long horizontal bearing extending substantially the length of the diameter of the insulator, and the line wire is not clamped in the insulator, nor is it given a sharp bend.

Further, in my insulator that portion of

the slot, which constitutes the passage for the line wire, lies wholly within the top of the body below the shoulder, so that the cover can be screwed down as tightly as desired without any possibility of clamping the line wire or interfering with its free movement.

In stringing a new line wire, it is not necessary to remove the caps 15 of the insulators, as the end of the wire can be easily pushed through the open part of the slot 13 extending through the top of the body 5. When it is desired to replace an insulator, the cap 15 can be unscrewed from the projection 11 and the wire passed through the slot in the projection, and the cap replaced.

It will be noted that the recess or slot to receive the wire renders absolute non-conductivity of the electric current, as the wire is entirely inclosed by the glass or porcelain body of the insulator. Moreover, there is no danger of the wire breaking or slipping from the insulators for the security of the line wire is not dependent upon the use of tie wires.

In practice slack may be taken from a mile of line in one operation by climbing but one pole.

What is claimed is:—

An insulator consisting of a substantially cylindrical body provided in its lower portion with a socket and having its upper portion exteriorly reduced to form a central vertical projection and a horizontal shoul-

der around the same, said projection being 35 exteriorly threaded and provided with a vertical slot extending downwardly through the said projection from the upper end thereof and through the said shoulder, forming laterally extending horizontally 40 disposed branches and providing a wire receiving passage through the insulator, the bottom of the slot and the branches being curved in cross section and the branches having their outer terminals beveled or 45 flared, and an interiorly threaded cap screwed on the threaded projection and engaging the said shoulders to confine a wire in the said slot, the laterally extending terminal branches lying entirely below the 50 shoulder, whereby the cap may be screwed down tightly on the said shoulder without clamping the wire or interfering with the free movement thereof through the said passage, and the cap being circumferentially 55 beveled at the exterior of its lower edge, so that beveled portions will lie above the flared terminals of the branches of the slot in any position of the cap, the bevel of the flaring terminals of the body and the cap 60 being of corresponding size.

In testimony, that I claim the foregoing as my own, I have hereto affixed my signature in the presence of two witnesses.

SILVESTER NUNN.
